UNITED STATES PATENT OFFICE.

ANDREW FRANCIS NEY, OF EAST KEW, VICTORIA, AUSTRALIA, ASSIGNOR TO BRYANT AND MAY PROPRIETARY LIMITED, OF RICHMOND, VICTORIA, AUSTRALIA.

MEANS FOR FEEDING BOXES OR THEIR CASES TO NESTING OR LABELING MACHINES.

Application filed June 18, 1923. Serial No. 646,067.

To all whom it may concern:

Be it known that ANDREW FRANCIS NEY, a subject of the King of Great Britain, residing at Glenelg, Edward Street, East Kew,

5 in the State of Victoria, Commonwealth of Australia, has invented Improved Means for Feeding Boxes or Their Cases to Nesting or Labeling Machines, of which the following is a specification.

10 This invention refers to box-closing or nesting machines with or without labeling mechanism or to box labeling machines, the former machines being used for inserting the receptacle or "inner" member of rectangular boxes into the open ended case or "outer" and having usually means for labeling the box members when nested, such machines being employed for instance in dealing with rectangular boxes for wooden 20 matches.

According to the nesting machines in use, the outers of the box are projected intermittently forward in succession from the bottom of a comparatively high manually supplied vertical magazine or hopper by means of a horizontal plunger and the inners of the box are advanced along a feed way at right angles to the travel of the outers and each in turn is inserted by means of a 25 plunger in an outer while the latter is momentarily stationary and in registration with an inner.

If the machine has box labeling mechanism combined therewith, the nested boxes 30 advance through said mechanism and are finally ejected.

Similarly in regard to match or other small box labeling machines the nested boxes or merely the outers thereof to be 40 labeled are first hand fed into a comparatively high magazine and the lowermost one projected to the labeling mechanism by means of a plunger.

In order to ensure correct alignment of 45 the box or outers with the horizontal plunger the interior of the vertical hopper must be a neat fit for the boxes consequently in order to ensure a constant downward feed and ensure the forward projection of the lowermost 50 box or outer at each stroke of the horizontal plunger it is essential on account of the lightness of the boxes or outers to provide a

comparatively high hopper so that it may contain a large stack and ensure weight that will to a certain extent minimize jamming 55 of the boxes or outers in the hopper.

Even with such a high hopper it is found essential for the operator in feeding boxes or outers into the hopper to exert a downward pressure on the stack.

On account of the feeding means referred to it is necessary for the operator to lift one hand to a fair height many thousands of times in a day's work and simultaneously exert a downward hand pressure while moreover the operator is obliged to stand in order to feed the boxes or cases into the top of the hopper. As a result it is found that the work of the operator involves considerable fatigue and the object of this invention is 70 to obviate this disability under which the operator labors, and for this purpose the invention provides improved feeding means for the cases or boxes that will obviate high arm lifting and downward pressure of the hand and permit the operator being seated if desired.

The invention is shown practically applied by the accompanying drawings of a box nesting and labeling machine.

In these drawings,

Fig. 1 is a plan (broken).

Fig. 2 a vertical sectional elevation on line II-II of Fig. 1.

Fig. 3 a vertical section on line III-III 85 of Fig. 1.

Figs. 4 and 5 are sectional detail views on lines IV-IV and V-V in Figs. 1 and 2 respectively.

Referring to the drawings, the outers of the boxes are designated 1 and the inners 2. The inners are advanced in a guide-way 3 by a belt 4 and are drawn in front of a plunger 5 by a reciprocating hook-ended arm 51 which plunger acting intermittently 90 pushes each inner 2 in turn into an outer 1 after which the complete box B is fed along a guide-way 50 to the well known labeling mechanism L.

According to this invention the outers 1 are delivered from a large hopper with an inclined chute for instance (not illustrated) upon an endless horizontal conveyor 6 which is preferably a flat belt travelling at right

angles to the direction of the boxes B and supported in a channel section guide-way 7 and passing around rollers 8, 9, said belt passing through a slot 47 in the bottom of 5 said guide way.

Motion is imparted to the spindle 10 of roller 8 by means of a belt 11 passing around a grooved pulley on spindle 10 and other pulleys 12, 13 and 14 the pulley 14 being rotated by the gear 15 of the machine.

The conveyor does not extend the full length of the guide-way 7 but stops a short distance from the advance end and a weighty roller 16 with a peripheral gripping band 15

17 of rubber or the like is mounted on arms 18 pivoted as at 19 to the sides of the guide-way 7 and adapted to rest preferably upon the second outer on the conveyor belt 6 at the pulley end 9.

20 The outers are pressed down upon the bottom of the last portion 19 of the guide-way beyond the conveyor by means of a flat spring hold down plate 20 fixed to the guide-way and which may be curved upwardly at 25 its entrance end to form a mouth and the outers are kept in line by means of a flat spring 43 in the guide-way.

30 The guide-way 7 is preferably about the height of six boxes or outers from the base plate 21 of the machine but could be lower and in any case is at a convenient height for loading the conveyor without necessitating the operator raising the hands to any extent.

35 At the advance or delivery end of the guide-way is a low vertical hopper 22 of rectangular cross section and slightly higher than the guide-way so as to hold about seven boxes or outers and its side adjacent the guideway is formed with an inlet 23 into 40 which the most advanced box or outer thereof is delivered by the action of the conveyor 6.

45 In the upper end of the hopper is a vertically reciprocated plunger 24 which, when in its lowermost position closes said inlet 23 so that the advanced outer abuts against said plunger till the latter rises and permits the outer to enter the inlet.

50 During the temporary stoppage of the line of outers the conveyor belt slips past under the outers but the frictional pressure of the weighty roller on one of the outers ensures that the outers on the end portion 19 of the guideway will advance when the plunger 24 is raised again.

55 The plunger 24 (Fig. 2) is fixed to an arm 25 guided in a slot 26 formed in one side of the hopper and in a guide 41 projected from the hopper and said arm is normally urged downwardly by a spring 27 and is fixed to a vertical rod 28. The latter is pivoted to an arm 29 by means of a pin 30 engaging a slot 31 in said arm which is pivoted as at 32 to the underside of the base plate. Said arm has an offset 33 carrying a

roller 34 in engagement with a cam 36 on shaft 42 said cam being formed with a peripheral recess 37. When the roller 34 engages this recess the plunger 24 reciprocates down and up and in doing so presses the 70 outers down the hopper so that the lowermost one is opposite an outlet 38 formed through the walls of said hopper. At the front of the hopper is a horizontal plunger 39 working in guides 40 and reciprocating 75 in the outlet 38 by means of a rod 44 on the underside of the plunger provided with a roller 45 engaging a cam race 46 on the shaft 42.

In operation the inners are delivered to 80 belt 4 and the outers to the conveyor 6 which delivers them into the upper end of the short vertical hopper 22.

In the position of the mechanism as illustrated, an outer has just entered the upper 85 end of the hopper while the plunger 24 is temporarily held in raised position by the cam 36 and the plunger 39 is drawn back after having pushed the lowermost outer forward. When the cam rotates about three 90 quarters of a revolution its recess 37 causes the vertical plunger to quickly descend and rise again thus depressing all the outers in the hopper compactly in the latter with the lowermost one opposite the horizontal plunger 95 which on advancing ejects the lowermost outer into the guideway 50 in which it advances to receive an inner projected by the plunger 5. The boxes B then advance along the guide-way 50 to the labeling 100 mechanism L, if such is combined with the machine.

It will be understood that the feeding mechanism is equally applicable to a labeling machine the only difference being that 105 boxes, i. e. nested outers and inners, are delivered to the short vertical hopper 22 and fed to the labeling mechanism.

Having now fully described and ascertained my said invention and the manner in 110 which it is to be performed, I declare that what I claim is:—

1. In a machine of the character described, a comparatively short vertical hopper with an inlet in one side and near the top, an endless horizontal conveyor belt continuously travelling in a guideway and passing through a slot formed therein, a weighty roller mounted on pivoted arms in said guideway, a hold down spring plate in the guideway in advance of said roller, a plunger adapted to be reciprocated vertically in said hopper and across the inlet therein and a horizontal ejector plunger operating in an outlet in the bottom of said hopper. 115 120 125

2. In a machine of the character described, a comparatively short vertical hopper with an inlet in one side and near the top, an endless horizontal conveyor belt continuously travelling in a guideway and passing 130

through a slot formed therein, a weighty roller mounted on pivoted arms in said guideway, a hold down spring plate in the guideway in advance of said roller, a vertically operated plunger in the upper end of said hopper mounted on a guided arm fixed to a spring controlled vertical rod connected with a pivoted arm carrying a roller supported on a cam, and a horizontal ejector plunger operating in an outlet in the bottom ¹⁰ of said hopper.

Dated this 3rd day of May 1923.

ANDREW FRANCIS NEY.
